UNITED STATES PATENT OFFICE.

HARLEY H. LA VERCOMBE, OF DETROIT, MICHIGAN.

DIE FOR RE-FORMING REAMERS.

1,266,830.

Specification of Letters Patent. Patented May 21, 1918.

Application filed April 25, 1917. Serial No. 164,347.

To all whom it may concern:

Be it known that I, HARLEY H. LA VERCOMBE, a citizen of the United States of America, residing at Detroit, in the county 5 of Wayne and State of Michigan, have invented certain new and useful Improvements in Dies for Re-Forming Reamers, of which the following is a specification, reference being had therein to the accompanying drawings.

This invention relates to a die for reforming reamers or the like whereby reamers which have been worn can be readily swaged to size without great trouble and with considerable regularity and accuracy.

The invention consists in the matters hereinafter set forth, and more particularly pointed out in the appended claims.

The drawing is a view in detail in end 20 elevation of a pair of dies which embody the invention, the work on which they are employed being shown in section between them.

As herein indicated, a bed die 1 is adapted 25 to span under the body 2 of a reamer and catch the oppositely disposed ribs or flutes 3 and 4 thereof, at one side on the working or under cut facet 6 and on the other side on the supporting or beveled back 7. Arranged 30 to coöperate therewith is a punch die 8, that spans over the reamer and operates with one spur 9 on the undercut facet on one side and on the other side with a part 10 on the facet 6.

As a result, a heated undersized reamer or 35 worm tool that is inserted in the die has its cutting ribs projected by the action of the die in swaging the root or body of the rib, beyond the required diameter of the finished tool so that it may be readily ground to

size. Preferably the dies do not operate 40 upon or molest in any way the cutting edge itself which is left in its pristine form. As a result a reamer that would otherwise have to be ground down is completely restored and is capable of the same usage as if completely new.

Obviously, changes in the details of construction may be made without departing from the spirit of the invention and I do not care to limit myself to any particular 50 form or arrangement of parts within the scope of the claims.

What I claim is:—

1. Means for reforming reamers, fluted tools and the like, comprising a bed die and 55 a punch die correspondingly recessed to clear an inserted tool and provided with gripping facets on the margins of the recesses that conform substantially to the opposite sides of the cutting flute or rib of the 60 tool between the root and cutting edge thereof, the pairs of opposing facets on one side of the recess being dressed reversely to the pair on the opposite side.

2. Means for reforming reamers, fluted 65 tools and the like comprising a bed die having a gripping facet that is the obverse of one flank of the rib of a tool and a punch die having a gripping facet opposing the bed die facet and dressed obversely to the 70 other side or flank of the rib of the tool.

In testimony whereof I affix my signature in the presence of two witnesses.

HARLEY H. LA VERCOMBE.
